CLAIM

The ornamental design for an electric fan, as shown and described.

DESCRIPTION

FIG. 1 is a perspective view of the claimed design;
 FIG. 2 is a front view of the claimed design;
 FIG. 3 is a rear view of the claimed design;
 FIG. 4 is a left side view of the claimed design;
 FIG. 5 is a right side view of the claimed design;
 FIG. 6 is a top plan view of the claimed design; and,
 FIG. 7 is a bottom plan view of the claimed design.
 The broken lines depict environmental subject matter only
 and form no part of the claimed design.

1 Claim, 7 Drawing Sheets(56)
